UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-DOOR OPERATING MECHANISM.

Application filed November 30, 1923. Serial No. 677,870.

To all whom it may concern:

Be it known that I, ARGYLE CAMPBELL, a citizen of the United States, residing at Chicago, in the county of Cook and State 5 of Illinois, have invented a certain new and useful Improvement in Dump-Door Operating Mechanisms, of which the following is a full, clear, concise, and exact description, reference being had to the accompanying 10 drawings, forming a part of this specification.

This invention relates to improvements in dump door operating mechanisms and the like.

15. The invention is especially adapted for dump cars having a rotatable door raising shaft supported in slotted bearings and adapted to move from a position adjacent the free edge of the discharge doors to a 20 position directly under the same.

25. My invention relates more particularly to the novel means employed for rotating the shaft and provides for increased leverage and a greater measure of safety for the operator than has heretofore been the case in the operation of cars of the type indicated. It has been the practice in the past to dispose the shaft rotating means directly 30 on the shaft and have the same movable in unison therewith but inasmuch as the heavy loads on the doors cause the shaft to move outwardly and rotate with great speed during the releasing operation of the doors, the operator is liable to injury by "back kick" of 35 the operating lever due to such sudden outward movement of the shaft and lever. It is therefore an object of my invention to overcome the disadvantage referred to by operating the shaft with means which will be 40 independent of the shaft and which will still function to rotate the shaft throughout its entire range of bodily movement.

45. Further, my invention resides in certain novel construction of parts and novel combinations of the parts, as will be more fully pointed out hereinafter.

In the drawings forming a part of this specification, Figure 1 is a sectional view of a portion of a car structure showing my invention applied to a dump car of the type 50 illustrated in my former U. S. Patent No. 1,284,056, dated November 5, 1918. As will be understood by those skilled in the art, I have only illustrated sufficient of the car 55 structure and door operating mechanism to

explain the invention. In actual practice, there will ordinarily be a plurality of doors co-operable with a single shaft and preferably two flexible connections or chains and associated elements with each door. Figure 60 2 is a side elevational view of that portion of the car which includes the operating mechanism and associated parts shown in Fig. 1. Figure 3 is a top plan view of the movable operating carriage with the operating 65 pawls shown mounted therein. Figure 4 is a transverse sectional view through the crossbeam taken on a line corresponding substantially to line 4-4 of Fig. 1 and showing the inner guide bracket. Figure 70 5 is a view similar to Fig. 1 except that it shows the commencement of the door releasing operation with the operating pawl in engagement with the ratchet wheel. Figure 6 is a view similar to Fig. 5 but 75 illustrating the position of the releasing operating pawl after the completion of the stroke, the initiation of which is shown in Fig. 5. Figure 7 is a view similar to Fig. 1 except that the shaft is located in the 80 recessed portion of the bearing and shows the door raising operation in progress, the movable carriage being shown as moved outwardly and the operating pawl positioned in co-operating engagement with the 85 ratchet wheel preparatory to an inward movement of the carriage for the purpose of displacing the pawl relatively to the shaft and inducing rotary movement of the said shaft. Figure 8 is a view similar to Fig. 90 6 except that it shows the completion of the movement, the initiation of which is shown in Fig. 6.

In said drawings, the invention is applied to a gondola type of car provided with a 95 longitudinal side sill 10 and transverse beam 11 secured thereto. One of the dump doors 12, of which the outer portion only thereof is shown in dotted lines, is indicated in Figs. 5 and 7 and includes a suitable frame- 100 work to which are secured brackets 13 each having a rounded serrated face 14. Connection is made between a longitudinally extending shaft 15 and the door by means of flexible elements 16 shown conventionally 105 in Fig. 7, of which there are preferably two associated with each door. On each shaft opposite each bracket 13 and co-operable with the serrated faces 14, are serrated 110 wheels 17 rigidly secured to the shaft 15.

The door shaft 15 is supported in bearing plates 18 secured to the transverse beams 11. Each of the bearing plates, as shown, is formed with an elongated slot 19 having 5 a depression 20 at the outer end thereof.

In this particular construction, the mechanism associated with the operation of the shaft consists of devices for securing the shaft against unintentional reverse rotation 10 thereof, during the raising operation and for positively locking the shaft in supporting position beneath the doors, and is designated broadly by the reference character A. There is also a separate mechanism for inducing 15 rotary movement of the shaft, said mechanism being designated broadly by the reference character B. In this general type of mechanism, as the shaft 15 is turned in a closing direction, the flexible elements 16 20 wind on the shaft thus lifting the doors until the latter are almost in closed position, at which time further winding of the members 16 on the shaft pull the same inwardly along the bearing slots until the serrated 25 wheels 17 engage with the rounded faces 14 of the brackets and, thereafter, the shaft is rolled under the doors, thus forcing the latter to fully closed position and also holding them closed with the load transferred to the 30 shafts.

The respective mechanisms A and B are disposed on opposite sides of the crossbeam 11. Said mechanism A is of the general type disclosed in my pending application, Ser. 35 No. 605,787, filed December 9th, 1922, and no claim is made to the same herein. Said mechanism A consists of a creeper 21 mounted on the shaft and movable in unison therewith, said creeper having an arm 22 (see 40 Fig. 1) outstanding therefrom and adapted to slide in a slotted bracket 23, a weighted pawl 24 pivotally mounted on the creeper and adapted to have co-operating engagement with a ratchet wheel 25 rigidly secured 45 to the shaft, and a cam 26 which is pivotally mounted on the creeper and adapted to lock the pawl 24 relatively to the ratchet wheel 25.

The mechanism B for imparting rotary 50 motion to the shaft consists of a reciprocating carriage member 26 having a pair of pawls 27 and 28 pivotally mounted thereon and co-operable with a ratchet wheel 29 which is rigidly mounted on the shaft. Said 55 reciprocating carriage member 26 is slidably mounted in suitable guides 30 and 31 spaced from each other and respectively secured to the car structure, said guide 30 being mounted on the side sill 10 and the guide 31 60 on the crossbeam 11. The movable carriage member 26 is preferably formed of channel shape with upwardly extending flanges 32-32 between which said pawls 27 and 28 are disposed and in different vertical planes, 65 bosses 33 serving to space the pawls from

each other. Pawl 27 operates to rotate the ratchet wheel in a direction to raise the shaft and pawl 28 operates to rotate the shaft in an unwinding direction or in a direction to provide for the release of the shaft from beneath the dump doors. 70

Said pawl 28 is preferably provided with a projecting finger 34 adapted to extend through a slot 134 in the member 26 and thereby enable the operator to readily grasp 75 the said pawl. The lower surface of the member 26 is provided with a series of teeth 35 with which an oscillatably mounted member 36 is adapted to co-operate through the medium of teeth 37 for the purpose of reciprocating the said member 26. While the said member 36 may be of any desired form, which will provide a handhold for the operator, a preferred construction is to form the same with a socket portion 38 within which 80 a suitable bar or tool 39 may be inserted. Said member 36 is pivotally mounted on a bracket 40 depending from the crossbeam 11 and disposed intermediately of the afore- 85 guides 30 and 31. 90

As shown in Figs. 1 and 2 there is provided on the bracket 40, a laterally projecting boss 41 extending beneath the movable member 26 and within a bearing portion 42 formed on the member 36. The boss 41 is 95 perforated at 43 and a bolt or pin 44 passed therethrough and through the member 36 for the purpose of maintaining the latter in position on the bracket 40, the outer wall of the socket portion 38 being perforated at 100 45 to permit of access to the said pin 44. The teeth 37, which are adapted to mesh with teeth 35, are suitably braced to the sides of the socket by means of flanges 46-46 and in order to protect the fingers of the operator from accidental jamming in the teeth, 105 guards are provided on each side of the teeth in the form of walls 47-47 (see Fig. 2) which are preferably formed integrally with the movable member 26, said walls further 110 protecting the teeth from ice and snow and preventing particles of rock or coal from lodging in the teeth which would thereby tend to interfere with the proper operation 115 of the mechanism. 115

The oscillatably mounted member 36 is 120 preferably so formed that it will move to a depending position by gravity as illustrated in Fig. 1 and, when in such position, serve to centralize the member 26. In order to assure that such centralizing action will be automatic, the lower end of the socket portion is weighted as indicated at 48. In instances where the car is only dumped at infrequent intervals, it is desirable to 125 retract the sliding member away from the car side and to this end I have provided a hook member 49 having one end secured in the hole 50 formed in the guide member 30 and the opposite end thereto engageable with a 130

hole 51 formed in the end of the oscillatably mounted member 36. The position of the parts 36 and 49 with the hook member 49 in engagement with the member 36 is indicated by dotted lines in Figure 1.

The operation of the device is as follows, assuming that the doors are closed and the parts positioned as shown in Fig. 1 with the operating pawls in inoperative position.

- 10 Having disengaged pawl 24 from the ratchet wheels 25, the operator inserts the bar 39 in the socket portion 38 and swings the same in a clockwise direction which has the effect of moving the member 26 inwardly. He then moves the pawl 28 into engagement with the ratchet wheel 29 when a counter-clockwise movement of the bar will reverse the movement of the member 26 and move the same outwardly to the position indicated in Fig. 6. During the movement of the bar from the position shown in Fig. 5 to that shown in Fig. 6 the displacement of the pawl 28 relatively to the ratchet wheel exerts a wedging action between the tooth of the ratchet wheel co-operating with the said pawl 28 and the movable bar 26, thereby inducing a rotary movement of the shaft. This operation is repeated until such time as the shaft is free of the door, and the weight of the door and lading will then be sufficient to rotate the shaft in an unwinding direction, due to the chain connection between the doors and the shaft, as will be understood. As the shaft travels outwardly, the ratchet wheel 29 frees itself from its engagement with the pawl 28 due to the fact that the same is arranged to drop by gravity to an inoperative position with respect to its ratchet wheel, it being necessary for the operator to manually position the pawl 28 in engagement with the ratchet wheel each time that the movable carriage is reciprocated, thereby permitting the shaft to travel away from and independently of the operating carriage and assuring safety to the operator. When the dump doors are in opened position, the shaft rests in the depressed portion 20 of the bearing and the operation of raising the doors to closed position is as follows: The weighted pawl 24 is first permitted to engage the ratchet wheel 25, the operative relation being maintained automatically thereafter as more fully explained in my said prior application. The operator then moves the operating bar 39 in a counter-clockwise direction thereby moving the carriage 26 outwardly. The pawl 27 is next manually brought into engagement with the ratchet wheel 29 and on a reversal of the movement of the carriage by the rotation of the bar 39 in a clockwise direction the parts assume the position shown in Fig. 8. These operations are repeated until the doors are lifted to fully closed position and

the shaft has traveled inwardly to a supporting position beneath the door, being drawn inwardly thereunder by reason of the flexible element 16 winding on the shaft. Because of the reciprocating action of the movable carriage, the rotary motion of the shaft is of an intermittent character and during the interval of time between successive engagement of the teeth, the shaft is maintained against reversal by the engagement of the pawl 24 with the ratchet wheel 25.

The invention is particularly applicable to a type of car wherein the shaft is located behind a sill above the lower level thereof and obscured from view and difficult of access to the operator but its application is not limited to cars of such construction and I contemplate the use of the same on cars of various designs. For instance, the device may conveniently be located on the end sill of a car when the dump doors extend over the trucks or it may be utilized on shafts employed with doors which extend transversely of the car.

While I have shown one embodiment of my invention, it is to be understood that the same is merely illustrative and I contemplate all changes which come within the spirit and scope of the claims appended hereto.

What I claim is:

1. In a door operating mechanism, the combination with an operating shaft adapted to be reciprocated by rotation thereof; of a ratchet wheel secured to the shaft; a pawl adapted to engage the said ratchet wheel; and means, independent of the shaft, for moving the pawl relatively to the shaft and thereby inducing rotary movement of the shaft.

2. In a door operating mechanism, the combination with an operating shaft adapted to be reciprocated by rotation thereof; of a movable member independent of the shaft; a ratchet wheel carried by the shaft; and a pawl adapted to engage the ratchet wheel and re-act against the movable member, said pawl being adapted to exert a wedging action between the movable member and the ratchet wheel on the shaft and thereby induce a rotary movement of the shaft.

3. In a car door operating mechanism, the combination with an operating shaft adapted to be reciprocated by rotation thereof; of a ratchet wheel secured to the shaft; a pawl adapted to engage said ratchet wheel; and a movable member operatively associated with the pawl in such a manner that movement of the member in one direction will change the relative position between the pawl and the shaft and thereby induce a rotary movement of the latter.

4. In a dump car, the combination with

- an operating shaft adapted to be reciprocated by rotation thereof; of means mounted on and adapted to travel in unison with the shaft for the purpose of securing the shaft against rotation; and means mounted on the car and independently of the shaft for rotating the said shaft.
5. In a dump car having a depending sill and a door operating shaft extending parallel to said sill located behind it above the lower edge of the sill and normally obscured from view, the combination with a ratchet wheel rigidly secured to the shaft; of means for rotating said shaft, said means including: an oscillatable member mounted independently of the shaft and below the level of the sill, and mechanism engageable with said ratchet wheel, said mechanism being adapted to be actuated by movement of said oscillatable member.
10. In a dump car door operating mechanism, the combination with an underframe; of a movable shaft; a ratchet wheel fixed to the shaft; a movable member provided with teeth; guides for said member; a pawl pivotally mounted on the movable member and co-operable with the ratchet wheel to rotate the same on movement of the movable member; and means for imparting movement to the movable member, said means including a hanger oscillatably mounted on the underframe and having a portion thereof formed concentrically with the axis of rotation thereof and having teeth formed thereon co-operable with the teeth on the movable member.
15. In a car door operating mechanism, the combination with a dump door; of a bodily movable shaft adapted to first raise the door and thereafter move bodily to supporting position beneath the door, said movement being effected by rotation of the shaft; a flexible connection between the shaft and the door; and means mounted on the car structure independently of the shaft for rotating said shaft, said means including: a movable member and a plurality of pawls mounted on the said member, one of the said pawls being engageable with the shaft to rotate the shaft in one direction and the other of said pawls being adapted to engage the shaft to rotate the same in the opposite direction.
20. In a dump car door operating mechanism, the combination with an operating shaft adapted to be reciprocated by rotation thereof; of a ratchet wheel secured to the shaft; a pawl adapted to engage the said ratchet wheel, said pawl having a depending portion constituting a fingerhold for the positioning of the pawl; and a movable member on which said pawl is mounted, said movable member having a perforation therein through which said depending portion of the pawl is adapted to extend.
25. In a car door operating mechanism, the combination with an operating shaft adapted to be reciprocated by rotation thereof; of a movable member independent of the shaft; a ratchet wheel carried by the shaft; a plurality of pawls disposed in different vertical planes, said pawls being oppositely disposed and mounted on independent pivots, one of said pawls being engageable with the ratchet wheel to rotate the shaft in one direction and the other pawl being engageable to rotate the shaft in the opposite direction; and means for imparting motion to the movable member.
30. In a car door operating mechanism, the combination with an operating shaft; of a ratchet wheel fixed to said shaft; a movable member provided with teeth on its under surface; a plurality of operating pawls mounted on said movable member, said pawls being oppositely disposed on the movable member and adapted to engage the ratchet wheel to rotate the shaft in opposite directions; and means for moving the movable member, said means including a toothed sector pivotally mounted on the car structure engageable with the teeth on said movable member.
35. In a car door operating mechanism, the combination with a dump door; of a bodily movable shaft adapted to first raise the door and thereafter move bodily to supporting position beneath the door, said movement being effected by rotation of the shaft; a flexible connection between the shaft and the door; and means mounted on the car structure independently of the shaft for rotating said shaft, said means including: a movable member and a plurality of pawls mounted on the said member, one of the said pawls being engageable with the shaft to rotate the shaft in one direction and the other of said pawls being adapted to engage the shaft to rotate the same in the opposite direction.
40. In a dump car door operating mechanism, the combination with a bodily movable shaft; of a ratchet wheel fixed to the shaft; a movable member; guides for said movable member; a pawl pivotally mounted on the movable member, said pawl being adapted to be manually positioned in co-operating engagement with the ratchet wheel and adapted to automatically assume an inoperative position with respect to the ratchet wheel; and means for imparting movement to the movable member whereby

the relation between the pawl and the ratchet wheel when in operative engagement may be varied and rotary movement of the shaft effected.

9. In a car door operating mechanism, the combination with an operating shaft adapted to be reciprocated by rotation thereof; of a ratchet wheel secured to the shaft; a pawl adapted to engage the said ratchet wheel, said pawl having a depending portion constituting a fingerhold for the positioning of the pawl; and a movable member on which said pawl is mounted, said movable member having a perforation therein through which said depending portion of the pawl is adapted to extend.

10. In a car door operating mechanism, the combination with an operating shaft adapted to be reciprocated by rotation thereof; of a movable member independent of the shaft; a ratchet wheel carried by the shaft; a plurality of pawls disposed in different vertical planes, said pawls being oppositely disposed and mounted on independent pivots, one of said pawls being engageable with the ratchet wheel to rotate the shaft in one direction and the other pawl being engageable to rotate the shaft in the opposite direction; and means for imparting motion to the movable member.

11. In a car door operating mechanism, the combination with a rotatable operating shaft; of a ratchet wheel fixed to said shaft; a movable member provided with teeth on its under surface; a plurality of operating pawls mounted on said movable member, said pawls being oppositely disposed on the movable member and adapted to engage the ratchet wheel to rotate the shaft in opposite directions; and means for moving the movable member, said means including a toothed sector pivotally mounted on the car structure engageable with the teeth on said movable member.

12. In a dump car, the combination with a door operating shaft adapted to be reciprocated by rotation thereof; of a member rigid with the shaft; a plurality of bracket guides secured to the car structure; a movable member adapted to have sliding motion within said guides; a bracket disposed intermediate the said guides, said bracket having a boss outstanding therefrom; an oscillating member pivotally mounted on said boss of the bracket and adapted to have cooperating engagement with the movable member whereby both of said members will move in unison; and a co-operating member between the movable member and the rigid member on the shaft whereby movement of the movable member will induce a rotary movement of the shaft.

13. In a dump car door operating mechanism, the combination with an operating shaft adapted to be reciprocated by rotation

thereof; of a member having movement in the plane of reciprocation of the shaft; a pawl member adapted to have operative engagement with the movable member and the shaft to rotate the same; and an oscillatable member co-operating with the movable member to displace the latter and move the same to either side of a central position, said movable member being adapted to be automatically returned to such central position when not in use.

14. In a dump car, the combination with a car side; of a door operating shaft disposed within the plane of the car sides and adapted to be reciprocated by rotation thereof; of a member independent of the shaft and movable in the plane of reciprocation of the shaft to a position beyond the limit of the car side, said member carrying a pawl adapted to co-operate with the shaft to rotate the same; and means for retracting the member away from the car side and locking the same in such retracted position.

15. In a dump car door operating mechanism, the combination with a side sill; of a rotatable operating shaft behind said sill and normally obscured from view; actuating means mounted independent of said shaft, said means being pivotally mounted

on the car structure below said sill; and means for transmitting the movement of said actuating means to said shaft.

16. In an operating mechanism for a pivoted dumping door, of a vehicle having a framework, the combination with a shaft mounted in said framework, adapted for rotation and bodily movement and arranged to move to a position beneath the free ends of the door to support the latter in closed position; of a flexible connection between the door and shaft by means of which the door is elevated and said shaft is rotated in one direction; means co-operable with said shaft to prevent accidental rotation of the latter in an unwinding direction when the door is being moved to closed position; and means for effecting rotation of said shaft in either direction, said means including an operating element supported independently of the shaft, a reciprocating element supported independent of the shaft; and co-operating devices on said reciprocating element and shaft.

In witness that I claim the foregoing I have hereunto subscribed my name this 23rd day of November, 1923.

ARGYLE CAMPBELL.
